CORN POPPER

Harry J. Lebherz, Frederick, Md., assignor to The Everedy Company, Frederick, Md., a corporation of Maryland

Application August 10, 1950, Serial No. 11,706

Term of patent 14 years

(Cl. D44—1)

To all whom it may concern:

Be it known that I, Harry J. Lebherz, a citizen of the United States, residing at Frederick, in the county of Frederick and State of Maryland, have invented a new, original, and ornamental Design for a Corn Popper, of which the following is a specification, reference being had to the accompanying drawing, forming a part thereof.

I claim:

The ornamental design for a corn popper, as shown.

HARRY J. LEBHERZ.
